UNITED STATES PATENT OFFICE.

JOHN C. LOWE, OF MINOT, NORTH DAKOTA.

COMBINED PHONOGRAPH AND TELEPHONE.

Application filed August 7, 1924. Serial No. 730,639.

To all whom it may concern:

Be it known that I, JOHN C. LOWE, a citizen of the United States, residing at Minot, in the county of Ward and State of North Dakota, have invented certain new and useful Improvements in Combined Phonographs and Telephones, of which the following is a specification:

My invention relates to improvements in combined phonographs and telephones.

My invention embodies the combination of a phonograph with a telephone, by means of which a telephone call is automatically answered by the machine at the station called, after which operation the machine returns to the starting position, and stops, and is in a condition to repeat the operation, at every subsequent call of the telephone. The invention enables the answering of the telephone calls automatically in the absence of anyone at the station called, by placing upon the machine, a phonograph record, having thereon a desired message to be conveyed to the person at the calling station.

In the accompanying drawings, forming a part of this specification, and in which like numerals are employed to designate like parts throughout the same,

Figure 1 is a plan view of a machine embodying my invention,

Figure 2 is an end elevation of same,

Figure 3 is a transverse section taken approximately on the line 3—3 of Figure 1,

Figure 4 is a rear side elevation of the machine,

Figure 5 is a transverse section taken on line 5—5 of Figure 4, and,

Figure 6 is an enlarged side elevation of the sound box, and associated elements.

In the drawings, wherein for the purpose of illustration is shown a preferred embodiment of my invention, the numeral 10 designates a box or casing, within which is mounted a motor, such as a spring motor or an electric motor, driving a train of gears 11. These gears are connected with a brake disk 12, rotating therewith. When the brake disk is held against rotation, the train of gears do not rotate.

Arranged above the casing 10 is a horizontal rotatable cylinder 13, receiving its rotation from a shaft 14, having a pulley 15 rigidly mounted thereon. This pulley is driven by a belt 16 engaging a pulley 17,

The numerals 18 and 19 designate feed and reverse shafts, which are arranged above the box, in parallel relation to the cylinder 13. These shafts have their ends journaled within bearings 20 and 21. The shafts 18 and 19 are screw threaded throughout substantially their entire length, as shown. The shaft 18 receives its rotation from a gear 22, rigidly mounted thereon and this gear engages a gear 23 rigidly mounted upon the shaft 19, and it is thus seen that the shafts rotate in opposite directions. The shaft 19 carries a gear 24, rigidly secured thereto, and this gear engages a gear 25, which is rigidly mounted upon the shaft 14, and is driven thereby.

Extending between the shafts 18 and 19, in parallel relation thereto, is a stationary guide shaft 26, rigidly attached to supports 27 or the like. Slidably longitudinally upon the guide shaft 26 is a carriage 28, which cannot turn thereon, by virtue of a key 29, slidably in a slot 30. The carriage 28 rigidly supports an overhanging arm 31, carrying the diaphragm chamber or sound box 32. The diaphragm chamber receives the usual diaphragm, having suitable connection with the stylus lever 33, which is vertically adjusted and carries the stylus 34. The stylus lever is raised and lowered by means of a bell-crank lever 35 pivoted at 36, to a bracket 37, rigidly secured to the arm 31. This bell-crank lever is connected with a link 38, which is shifted by means to be next described.

The carriage 28 has a tubular extension or hub 39, rigidly secured thereto, and this tubular extension pivotally receives a collar 40 formed upon the central portion of a feed bar 41. This feed bar is provided at its ends with curved heads 42 and 43, having screw threaded recesses 44, which engage the feed and reverse shafts 18 and 19, as shown. The collar 40 is provided in its top with a spring 100 pressed bolt 45, for insertion within recesses or depressions 46 and 47, as more clearly shown in Figure 5. An upstanding inverted V-shaped frame 48 is rigidly mounted upon the feed bar 41, and projects above the same, and is pivotally connected with the link 38, as shown at 49.

The starting means embodies an electromagnet 50 arranged within the box 10, and which is connected in the ringing circuit of the telephone. A horizontally swinging

electro-magnet 50, and is retained in the normal position by a spring 52. The armature 51 carries a spring pressed pawl 53, engaging a horizontally rotatable ratchet wheel 54, having teeth for more than one-half of its circumference, while the remainder is smooth. This ratchet wheel is rigidly mounted upon a vertical rotatable shaft 55, projecting above the box 10, and having a horizontally arranged cam 56 rigidly mounted thereon. The ratchet wheel 54, Figure 4, has a link 57, arranged there-beneath, and pivoted thereto, and this link is pivotally connected with a slide rod 58, operating within a guide 59. The slide rod 58 carries a compressible brake shoe 60, to engage and disengage the brake disk 12.

The numeral 61 designates a stationary shifting cam, arranged near one end of the shafts 18 and 19, and 62 designates a second stationary shifting cam, arranged near the opposite end of the shafts 18 and 19. These cams have upper inclined faces 63. The cams 61 and 62 are disposed upon opposite sides of the guide shaft 26, and the cam 61 is arranged in the path of travel of a spring pressed pin 64, carried by the feed arm 41, while the cam 62 is arranged in the path of travel of a spring pressed pin 65, carried by the feed arm 41. The pins 64 and 65 are disposed upon opposite sides of the tubular extension 39, as shown.

The carriage 28 is provided with a lateral extension 70, to which is pivoted a depending trip 71, having a knee joint therewith. This trip is free to swing to the right, but is rigid with respect to swinging movement to the left, Figure 4.

The numeral 72 designates the transmitter of a telephone of the usual construction, and a tube 73 is secured upon this transmitter and leads to the diaphragm casing 32.

In Figure 6, the numeral 74 designates the hook of the telephone, which closes the talking circuit at the points 75, when the receiver is raised. The receiver may remain upon the hook, and wires 76 and 77 are connected across the points 75, and lead to stationary contacts 78 and 79, carried by the arm 31, and insulated therefrom. It will be seen that the talking circuit will be closed, as if the receiver were raised, when the contacts 78 and 79 are electrically connected. These contacts are electrically connected by means of a swinging contact 80, movable into, and out of engagement therewith, and this swinging contact is rigidly mounted upon the rock shaft 36, pivoted in the bracket 37, and having the lever 35 rigidly mounted thereon.

The operation of the machine is as follows:

The party at the station to be called, places upon the cylinder 13 a record containing the desired message, and the ele-

ments of the machine are in the position, as shown in Figure 1. The carriage 28 has been shifted to the left, to approach the end of the reverse travel, but the head 43 still engages the reverse screw 19. The brake element 60 now holds the brake disk 12 against rotation. When the ringing circuit is closed, magnet 50 is energized, and the armature 51 is oscillated, and the ratchet wheel 54 turned. This movement of the ratchet wheel withdraws the brake element from the brake disk 12, and the motor is set in action. The carriage 28 now completes its movement to the left, the pin 64 riding up the shifting cam 61, and this shifts the feed bar 41 upon its pivot, causing head 43 to disengage reverse screw 19, and head 42 to engage feed screw 18. When this occurs, link 38 is drawn rearwardly and the bell-crank lever 35 is swung downwardly, causing the stylus 34 to engage the record. The contact 80 is also moved into engagement with contacts 78 and 79, and the talking circuit is closed. The head 42 engaging the feed screw 18, causes the carriage 28 to travel to the right, in its feeding movement, until the pin 65 rides upon the shifting cam 62, at which time the feeding movement is stopped. The feed bar 41 is again shifted so that the head 42 disengages the screw 18 and the head 43 engages the screw 19. The reverse movement of the carriage will now occur, and the trip 71 will engage the cam 56, and turn the same in the direction of its arrow. This cam turns the ratchet wheel 54, and by the time the carriage approaches the end of its reverse movement, the brake element 60 will engage the brake disk 12, sufficiently, to stop the motor, and the ratchet wheel 54 will be restored to its starting position. The stylus 34 is elevated, and the talking circuit opened, upon the starting of the reverse movement of the carriage.

It is to be understood that the form of my invention herewith shown and described is to be taken as a preferred embodiment of same, and that various changes in the shape, size, and arrangement of parts, may be resorted to, without departing from the spirit of my invention, or the scope of the subjoined claims.

Having thus described my invention, I claim:

1. A phonograph comprising a rotatable cylinder, a motor, a carriage to travel longitudinally of the cylinder, sound reproducing means connected with the carriage including a vertically movable stylus, feed and reverse screws extending longitudinally of the cylinder, a feed bar pivotally connected with the carriage and having screw threaded portions to alternately engage the feed and reverse screws, means connected with the feed bar to raise and lower stylus, driving connecting means between the motor

- and the feed and reverse screws, cams arranged near the ends of the feed and reverse screws to shift the feed bar upon its pivot, a brake device to control the operation of the motor, a ratchet wheel having teeth upon a portion of its periphery and connected with the brake device, an electrically operated pawl device to engage the ratchet wheel, a cam to turn the ratchet wheel, and a trip connected with the carriage to engage the last named cam.
2. A phonograph comprising a rotatable cylinder, a motor to drive the cylinder, a stationary guide extending longitudinally of the cylinder, a carriage sliding longitudinally of the guide and held against lateral movement thereon, a support arm mounted upon the carriage and arranged near the cylinder, sound reproducing means carried by the support arm and including a vertically movable stylus, feed and reverse screws extending longitudinally of the stationary guide and disposed upon opposite sides thereof, a feed bar pivotally connected with the carriage and extending upon opposite sides thereof and having screw-threaded parts to engage with the feed and reverse screws, cams arranged near the ends of the path of travel of the carriage to shift the feed bar upon its pivot, a member attached to the feed bar, a bell-crank lever engaging the stylus to raise it, a link connecting the member and bell-crank lever, driving connecting means between the motor and the feed and reverse screws, a brake device for controlling the operation of the motor, means actuated by the carriage to set the brake device, and electrical means to release the brake device.
3. Apparatus of the character described, comprising, a rotatable cylinder, a carriage traveling longitudinally of the cylinder, spaced feed and reverse screws extending longitudinally of the cylinder, a swinging feed bar connected with the carriage and having screw-threaded parts to engage with the feed and reverse screws, cams arranged near the ends of the path of travel of the carriage to shift the feed bar upon its pivot, sound reproducing means supported by the carriage and including a vertically movable stylus, means automatically operated upon the movement of the feed bar upon its pivot to raise or lower the stylus, a motor to drive the cylinder and feed and reverse screws, a brake device for controlling the operation of the motor, means actuated by the carriage to set the brake device, electrical means including a telephone ringing circuit to release the brake device, a telephone talking circuit, and means to automatically close the telephone talking circuit independently of the position of the receiver, when the stylus is lowered.
4. The combination with sound reproducing mechanism including a self-starting motor, a brake element controlling the action of the motor, a co-acting brake element to engage with the first named brake element, means to move the co-acting brake element including a ratchet wheel, a pawl to engage the ratchet wheel, electrical means to reciprocate the pawl, a telephone ringing circuit connected with the electrical means, and a telephone talking circuit associated with the sound reproducing mechanism, and means actuated by a movable part of the sound reproducing mechanism to move the co-acting brake element.

In testimony whereof I affix my signature.

JOHN C. LOWE.
